[57] CLAIM

The ornamental design of an automobile steering lock, as shown and described.

DESCRIPTION

FIG. 1 is a top plan view of an automobile steering lock showing my new design;

FIG. 2 is a front elevational view thereof;

FIG. 3 is a rear elevational view thereof;

FIG. 4 is a bottom plan view thereof;

FIG. 5 is a right end elevational view thereof;

FIG. 6 is a left end elevational view thereof;

FIG. 7 is a front elevational view of a second embodiment thereof, the rear being a mirror image;

FIG. 8 is a bottom plan view of FIG. 7, the top being substantially a mirror image of FIG. 1, the only differences residing in the configuration of the handle grip element and the length of the handle arm;

FIG. 9 is a left side elevational view of FIG. 7; and

FIG. 10 is a right side elevational view of FIG. 7.
